INVENTOR.

James H. Collins,

BY *J. Stuart Freeman,*

ATTORNEY.

UNITED STATES PATENT OFFICE.

JAMES H. COLLINS, OF HARRISBURG, PENNSYLVANIA.

RADIATOR.

1,297,447.

Specification of Letters Patent. Patented Mar. 18, 1919.

Application filed February 23, 1918. Serial No. 218,690.

To all whom it may concern:

Be it known that I, JAMES H. COLLINS, a citizen of the United States, residing at Harrisburg, in the county of Dauphin and 5 State of Pennsylvania, have invented certain new and useful Improvements in Radiators, of which the following is a specification.

The object of this invention is to provide 10 improvements in fluid heated radiators, and particularly with regard to increasing the efficiency thereof with a given amount of fluid available.

Another object is to provide a radiator of 15 large external radiating area, which ordinarily means an increased interior cubical content, but in this case materially decreasing said cubical content without in any way affecting the area of the said external radiating surface.

Still another object is to provide a means for accomplishing the result above stated, which at the same time will not absorb and disburse any of the calories carried into the 25 radiator by the particular fluid in use, which may be air, vapor, steam, water, or the like.

And a still further object is to provide a means for the purpose above stated such as will be capable of providing a vacuated interior, thus preventing said means from conveying heat from said fluid to the exterior of the radiator proper, said means by virtue of its vacuated interior also acting as a heat reflecting means, destined thereby to increase the efficiency of the heated fluid in 30 affecting the temperature of the exterior radiator casing, and thereby to the surrounding atmosphere.

With these and still further objects in view, the preferred embodiment of the invention consists in certain novel details of construction and operation as are fully brought out in the following specification when read in conjunction with the accompanying drawings, in which Figure 1 is a vertical, diametrical section of a device embodying the broad idea of the invention; and Fig. 2 is a transverse horizontal section on the line 2—2 of Fig. 1.

Referring to the drawings, a casing is provided of any desired shape whatsoever, but in this instance comprising a closed upper portion 1 and substantial cylindrical walls 2, which latter are partially closed at 55 their lowermost portion by means of a wall 3, provided with an internally threaded

aperture 4, surrounded by a bushing 5, said last-named wall being integral if desired, but at least unitarily associated with the 60 said walls 2.

The said casing is provided with an inlet 6 through which any desired heated fluid may pass, such as steam, water, gas, or the like, by means of a pipe 7, the flow of said fluid being regulated at will by means of the 65 valve 8 in said pipe. In common practice, it is preferable to place the fluid-inlet to the casing adjacent to the lowermost portion of the latter, while preferably opposite thereto and adjacent to the uppermost portion of 70 said casing, there is provided an outlet 9 from which a pipe (not shown) may lead a heated liquid, when such is used, or in which outlet in the present instance is shown a valve 10, by which gaseous fluids are allowed 75 to escape, as they become cooled and have their place within the radiator casing occupied by more heated gases.

Extending substantially throughout the length of the said casing and preferably 80 to within a short distance of the uppermost wall thereof, is a suitably shaped tube 11, which is closed at its uppermost end 12, and provided adjacent to its lowermost portion with screw-threads 13 by which it is 85 tightly secured within and supported by the walls of the opening 4 in the casing-wall 3. The lower end of the said tube preferably extends slightly beyond and below the said casing-wall 3, and is provided with 90 a suitable cap 14 and with any desired form of valve or pet-cock 15, through which a vacuum may be obtained within said tube, and by which said vacuum may be maintained after being accomplished by means of 95 a suitable pump 16, or other suitable vacuating mechanism. In order to insure the air-tightness of the tube 11 and the radiator casing 1—2—3, gaskets 17 and 18, respectively, are provided against which the cap 100 14 is screwed.

In the operation of this device, when a heated fluid is permitted to enter the radiator casing, the latter will experience a rise in temperature approaching that of the fluid 105 admitted thereinto, and thereby heating the surrounding atmosphere by radiation, contact and convection, to no less degree than were the vacuated tube 11 omitted from within the casing, and at the same time 110 necessitating the use of a considerably less volume of fluid by reason of the interior

cubical contents of the said casing being partially occupied by the said tube. However, while the fluid and exact extent of the increased efficiency is not definitely known at this time, it has been found that a great saving in heating fluid is made possible by proportionately decreasing the amount of fuel necessary to generate either the fluid itself, as in the case of steam, or the degree to which the same is heated.

Furthermore, it has been definitely noted that while this increased efficiency is present and clearly obvious even while said tube is not vacuated, but is filled with air at or about atmospheric pressure, said efficiency is greatly increased by creating a vacuum within the said tube, and while all of the causes thereof may not be known at this time, it is believed that as there is nothing within the said tube to absorb heat from the fluid within the radiator casing, said tube in effect becomes a heat radiating, or, probably more correctly speaking, a heat-reflecting surface, thus insuring a greater transmission of heat-calories from the fluid to the exterior casing, with its consequent greater temperature raising efficiency as regards the surrounding atmosphere.

Therefore, while it has been found more advantageous to maintain a vacuum within the interior tube, it is to be understood that increased efficiency has been found even

when no vacuum is employed and with the air within said tube at or about normal atmospheric pressure.

Having thus described my invention, what I claim and desire to protect by Letters Patent of the United States is:—

1. A radiator unit, comprising a shell having a fluid inlet and an outlet, a cell supported within said shell by one of the walls of the latter and extending through said supporting wall, and means to seal said cell after vacuating said cell.

2. A radiator unit, comprising a shell having a fluid inlet and an outlet, a cell supported within said shell by one of the walls of the latter and extending through said supporting wall, means to seal said cell, and means to permit the vacuating of said cell.

3. A radiator unit, comprising a shell having a fluid inlet and an outlet, a cell supported within said shell by one of the walls of the latter and extending through said supporting wall, means to seal said cell, and means within said sealing-means to permit the vacuating of said cell.

In testimony whereof I have affixed my signature in the presence of two witnesses.

JAMES H. COLLINS.
